UNITED STATES PATENT OFFICE.

BENJAMIN F. MAYO, OF SALEM, MASSACHUSETTS, ASSIGNOR TO UNITED SHOE MACHINERY COMPANY, OF BOSTON, MASSACHUSETTS, A CORPORATION OF NEW JERSEY.

HEEL-NAILING MACHINE.

No. 884,513.

Specification of Letters Patent.

Patented April 14, 1908.

Application filed January 10, 1902. Serial No. 89,137.

To all whom it may concern:

Be it known that I, BENJAMIN F. MAYO, a citizen of the United States, residing at Salem, in the county of Essex and State of Massachusetts, have invented an Improvement in Heel-Nailing Machines, of which the following description, in connection with the accompanying drawings, is a specification, like letters on the drawings representing like parts.

This invention relates to heelng machines and more particularly to machines for attaching heels to boots or shoes.

The invention is herein shown and described as embodied in a machine of the type shown in United States Letters Patent, No. 694,656, dated March 4, 1902, in which a nail block is supplied with nails from automatic assorting and distributing apparatus. The machine described in said patent contains a die-bed spindle moved vertically in suitable guideways by a toggle and link, the latter being actuated at the proper times by a clutch controlled shaft which when started is rotated twice in succession and then stopped, the upper end of the die-bed spindle having a driver-head supporting a series of drivers. The said machine also includes a nail-assorting mechanism adapted to supply nails with their heads all in one direction to a nail-carrier or transferring device shown as comprising a swinging arm movable by the operator from the position where the transfferer is supplied with nails to a position over the nail-block. In the latter position the nail-support is withdrawn letting the nails drop from the transfferer into the nail-block.

In this present invention I have provided a nail-guide to guide nails passing from the transfferer into the nail-block; and I have also provided the transfferer with a gage to better sustain nails of different lengths. I have also provided a novel heel and top-lift holder and have actuated it in novel manner; and have provided a novel connection between the nail-transfferer and the device common to said patent for preventing the starting of the shaft for operating the die-bed spindle when the transfferer is not in its nail-receiving position.

Figure 1, in elevation, represents part of the frame of a heel-nailing machine provided with a nail-block holder, a transfferer, and a heel and top-lift carrying plate embodying my invention, the transfferer being shown

in nail-receiving position; Fig. 2 is a detail showing part of the nail-block head, the cam for operating the heel and top-lift holder, and the locking device for maintaining the holder in position while a heel is being nailed to the shoe; Fig. 3 is a detail showing what I shall designate as a tripping device for effecting the release of the locking device to enable the heel and top-lift holder to be moved for putting the top-lift in attaching position; Fig. 4 is a detail showing in elevation the nail-block head, part of the nail-block, and part of the plate carrying the heel and top-lift holders and said locking and tripping devices; Fig. 5 shows the nail-receiver of the nail-transfferer removed; Fig. 6 is a section of the nail-transfferer with the nail-sustainer in operative position; Fig. 7 is a view showing the parts represented in Fig. 6, but with the nail-sustainer removed, the nail-transfferer being shown as occupying a position above the nail-block; Fig. 8 is a plan view of the parts shown in Fig. 1; Fig. 9 is a like plan view with the transfferer in position to give up its nails to the nail-block; Fig. 10 is a section in the dotted line α' , Fig. 8; Fig. 11 is a plan and side view of the adjustable stop for positioning the heel and top-lift holder; Fig. 12 is a partial front elevation on a smaller scale showing the framework, chiefly to show the device for actuating the driver-head and nail-block head; and Fig. 13 is a side elevation of the parts shown in Fig. 12.

The framework A, the clutch controlled shaft A', the clutch controlling lever D, the shaft a having the toes a' and a'' , the lug a^5 carried by the rod a^6 and controlled as to its position by the position of the nail-transfferer so that the shaft A' may be started by the operator through the treadle a^9 only when the transfferer is in its position to receive nails; the drivers d ; the spring-controlled link f^4 , connected with the heel and top-lift plate and acting normally after the heel has been attached to turn said plate automatically and put the top-lift in attaching position; the die-bed spindle E^4 moved by the toggles E , E' , and link G , and the post c^2 sustained by the frame A and constituting the pivot for the nail-transfferer, are and may be substantially as shown and described in said patent.

The shape of the driver carrying head E^6 differs from that shown in said patent, in

that it has at its opposite ends, see Figs. 1 and 12, bearings closed by caps E^{8X} , to receive grooved collars from which depend guides E^8 which sustain the lower ends of 5 strong springs E^9 , said springs receiving through them reduced portions E^{7X} of rods E^7 fitted to slide in the bearings of the head E^6 , the lower ends of the rods being extended through said guides, said springs acting at 10 their upper ends against washers E^{8X} abutting against shoulders on said rods, and keeping them and the nail-block head a^8 elevated above the driver-head E^6 . The nail-block head carries a nail-block a^{10} provided with holes for the reception of nails and over which moves the heel and top-lift holder e^{10} to be described.

As the spindle E^4 is lifted, a heel being held in the heel-holder, the driver-head E^6 20 and nail-block head a^8 rise in unison until the upper side of the heel meets the sole of the shoe held on a jack, and after the pressure of the nail-block on the heel has been exerted to the proper amount measured by 25 the springs E^9 , the nail-block head is stopped, but the driver-head continues to rise, sliding upwardly on the rods E^7 and compressing the springs E^9 , the upward movement of the driver-head independently of the nail-block 30 head causing the drivers d to rise in the holes in the nail-block, and acting against the heads of the nails in said block drive them from the block into and through the heel to attach the same to the sole.

35 The provision of sliding the driver-head on the rods sustaining the nail-block head and compressing the springs E^9 is not of my invention and is not herein claimed.

The lower end of the post c^2 has clamped 40 upon it by a clamping screw a^{12} the split hub of an arm a^{13} having at its opposite end a split sleeve which receives the shank of a catch a^{14} forming part of means for holding the nail-transferrer in its nail-receiving position. The shank of the catch is clamped in 45 said sleeve by a clamping screw a^{15} . The arm a^{16} of the transferrer shown has at one end a hand-piece a^{17} and at its opposite end is secured to a hub a^{18} , which is free to turn 50 on the post c^2 . The transferrer has another arm a^{19} , provided with a stud a^{20} which enters a hole in a sliding rod a^{21} free to reciprocate in a sleeve a^{22} connected with the upper end of the rod a^6 , before described, said rod having at its lower end, as shown in Figs. 2, 9, 55 10, 12 and 13, the lug a^5 which co-operates with the stop - finger a^2 common to said patent.

As the transferrer is swung from its position shown in Fig. 8 into the position shown in Fig. 9, so that it may give up its nails, it immediately turns the lug a^5 into position underneath the toe a^2 so that under no circumstances can the machine be started to acc-

60 tuate the drivers until after the transferrer

has supplied the nail-block with nails and has been returned into its normal starting position. The transferrer is locked automatically in its normal nail-receiving position by a latch b^{10} carried by the arm a^{16} 70 thereof, said latch being actuated by a spring b^{12} to engage the catch a^{14} referred to. The arm s^{16} of the transferrer is provided near its outer end with a hole in which is placed a nail-receiver b^{14} , represented as a circular 75 plate having a rim b^{15} to rest upon said arm, said receiver having in practice a great number of nail holes to provide for different nailings, and being represented as chambered at its upper side to receive a gage plate b^{16} 80 having its nail-holes arranged in the proper order for the particular driving desired.

The gage plates used will vary as to the arrangement of their nail holes according to the outline of nailing required. The gage plate 85 for short nails may lie in the bottom of the recess of the receiver, as in Fig. 6, or for long nails it may occupy a position near the top of said recess, see Fig. 7, the gage plate at such time being supported on a ring, as b^{17} , which 90 may be of wire sprung into the recess in the receiver. The gage plate has two guide pins b^{18} to enter holes 4 in the receiver, that the nail holes in the gage plate and receiver may be kept in alinement. The nail-block a^{10} 95 has holes b^{19} to receive the nails 2 from the transferrer. The arm a^{16} of the transferrer is provided with a stud c^{10} upon which is pivotally mounted a nail-sustainer c^{12} , the free end of which occupies a position under the 100 nail-receiver, as represented in Figs. 1 and 6, when the nails are fed into the said receiver from the usual nail-assorting mechanism, not shown, but which may be common to said patent, said nail-sustainer keeping the nails 105 in the holes of the receiver while the transferrer is being moved from its nail-receiving into its nail-delivering position. The nail-sustainer c^{12} has projecting from one side of it a lip c^{13} , and near the lip the sustainer has a 110 hole c^{14} , which is entered by a stud c^{15} in the transferrer arm a^{16} , said stud acting as a catch to maintain the sustainer in its operative position, as represented in Figs. 6 and 8, to prevent the nails in the receiver from dropping 115 therefrom. The nail-sustainer has a lug c^{16} , suitably bent and engaged by one end of a spring c^{17} , the opposite end of the spring entering a hole in the stud a^{20} before referred to, said spring when the sustainer is released 120 from the stud c^{15} immediately moving the sustainer from under the receiver, see Figs. 7 and 9, freeing the nails so that they drop by gravity into the holes of the nail-block.

As the nail-receiver b^{14} of the transferrer arrives in its nail-delivering position, Fig. 9, the holes therein having been placed in alinement with the holes in the nail-block, the ear c^{13} of the nail-sustainer meets the stop c^{13X} 125 that depresses the sustainer and disengages 130

the same from the stud c^{15} which extends downwardly from the lower side of the transfer arm a^{16} as before described, permitting the spring c^{17} to act immediately and move the nail-sustainer from the position shown in Fig. 6 allowing the nails standing in the holes of the nail-receiver to immediately drop and pass through the holes in the nail-guide d^{10} and enter the holes in the nail-block. The nail-sustainer is formed of a thin plate which has sufficient resiliency to permit it to be sprung down to disengage it from the stud c^{15} . The nail-sustainer when released as described is moved by the spring c^{17} into the position shown in Fig. 9, the end of the arm of the sustainer beyond its pivotal point c^{10} striking the hub a^{18} of the transfer arm and stopping the sustainer in said position.

In order that the holes in the receiver may be exactly aligned with the holes in the nail-block, I have provided the transfer arm a^{16} with an adjustable stop c^{18} which is arranged to contact with a nut 10 screwed upon a threaded projection 12 of the nail-block holder. The nail-sustainer c^{12} has a lip c^{20} which, as the transfer arm is returned from its position, Fig. 9, into the position, Fig. 8, meets the shoulder 3 of the catch a^{14} which forces the nail-sustainer into operative position under the receiver as the transfer arm comes into nail-receiving position. Stopping the sustainer in advance of the transfer arm a^{16} on the return movement permits the lower end of the stud c^{15} on said arm to move to a position over the hole c^{14} of the sustainer, said stud locking the sustainer in proper position to support the nails discharged from the nail-assorting mechanism into the holes of the gage plate and the nail-receiver.

The holes in the receiver must be exactly positioned with relation to the usual delivery tubes supplied with nails from the nail-assorting mechanism, which may be such as provided for in said patent, or any suitable tubes leading from a nail-assorting mechanism, and to insure this position I employ an adjustable stop c^{21} carried by the arm a^{16} , said stop also meeting the face 3 of the catch referred to.

When the transfer arm is to be turned from the position, Fig. 8, where the nails are supplied to its receiver, the operator by pulling on the hand-piece a^{17} will disengage the hook b^{10} from the catch a^{14} and swing the transfer arm by hand toward nail-delivering position until the stop c^{18} meets the nut 10.

In machines as heretofore constructed difficulty was sometimes met with in guiding and delivering nails correctly into the holes b^{10} of the nail-block; said difficulty arising from the fact that the underside of the nail-receiver, when the transfer arm was in position to deliver nails, stood in a plane above that in which the top of the heel and top-lift

carrying plate moved, and consequently there was considerable space between the upper side of the nail-block a^{10} and the underside of the receiver. When this space is greater than the length of the nail, the nails cannot be delivered with certainty into the holes in the nail-block and consequently I have provided a nail-guide d^{10} , having a series of holes 5 which are in alignment with the holes in the nail-receiver, and this nail-guide is sustained for the best results from the underside of the receiver by means of stands 7, represented in full lines in Fig. 1 and also in Fig. 7. The nail-guide is located sufficiently below the lower end of the nail-receiver and the lower side of the arm a^{16} to afford space for the nail-sustainer.

Figs. 6 and 8 show the nail-sustainer in position to sustain the nails, it occupying the position shown until the arm a^{16} arrives in the position, Fig. 9, at which time the sustainer, as has been described, is withdrawn from under the heads of the nails, letting the nails, see Fig. 7, drop through the holes in the nail-guide and enter the holes b^{10} in the nail-block. The nails dropped into the holes are arrested in usual manner by the upper ends of the drivers d contained in the nail-receiving holes in the nail-block, as provided for in said patent.

I believe I am the first to provide a nail-guide, occupying a position between the nail-transfer arm and the top of the nail-block, and I desire to claim this feature broadly, irrespective of its construction, and in whatever form it may be employed. The lower side of the nail-guide is located in a horizontal plane as close as practicable to the upper side of the nail-block and all the nails in the receiver and resting upon the sustainer will drop from the receiver and be guided through the holes 5 of the nail-guide on their way into the holes b^{10} of the nail-block.

The arm a^{16} of the nail-transfer arm has an ear d^{13} and extended upwardly therefrom is a projection d^{14} , which, when the transfer arm is moved toward position to receive nails, meets the inclined face of a pivoted contact piece 25 at the end of a rod a^{10x} , held loosely in a boss or arm A^{10} extended from the framework and shown only in Fig. 1, which moves a suitable device to start into operation nail-assorting mechanism, as provided for in said patent, so that said mechanism may immediately discharge a series of nails to enter the holes in the receiver of the transfer arm. In the movement of the transfer arm toward the nail-block the contact piece 25 turns about its pivot to permit the projection d^{14} to pass by the rod a^{10x} .

The stud c^{19} on the transfer arm a^{16} has connected to its lower end, as herein shown, a jointed actuator d^{15} , represented as composed of two parts united by a pin d^{16} , said parts being further connected by a spring d^{17} ,

which spring and pin will permit the free end of the actuator to be turned down if it should be in the way of a roller d^{18} when it was descending, the spring returning the free end portion of the actuator to normal position when permitted to do so.

The free end of the actuator is curved and in the movement of the transfrerer from the position, Fig. 8, into the position, Fig. 9, 10 meets the roller d^{18} , shown by full lines in Fig. 4, and partially in Fig. 2, and by dotted lines in Figs. 8 and 9, said roller being mounted on a stud d^{19} extended downwardly from the heel and top-lift holding plate e^{10} which 15 is pivotally mounted on the stud 12 referred to, the latter being extended through and fixed in the hole 8 in a small ear 9 extending from the nail-block head a^9 .

In Fig. 4, which shows the roller d^{18} in full lines, it will be noticed that the stud d^{19} is extended downwardly and has a shape in cross section substantially as represented in Fig. 2. Whenever the heel and top-lift holding plate e^{10} occupies the position shown in Fig. 9, 25 which is its position when a heel is to be attached, the stud d^{19} , see Fig. 2, is caught by an arm d^{22} of a spring-controlled locking device having a tail d^{23} and pivoted at d^{24} on a block d^{25} , adjustably connected by a screw 30 d^{26} with an arm d^{27} of the nail-block head a^9 . The adjustment of the block d^{25} provides for varying the position of the heel and top-lift holding plate e^{10} so that the side of the heel held therein may be properly positioned with 35 relation to the nail holes in the nail-block. The nail-block head a^9 is also provided with an ear 10^x , see Fig. 2, having a hole 13 in which is received the stem 14^x of an adjustable stop 14 shown in Figs. 8, 9 and 11. 40 When the heel and top-lift holding plate e^{10} is moved into position to present a top-lift to the attaching mechanism an ear e^{14} on said plate strikes against one side of the stop 14 to arrest the plate e^{10} in proper position. 45 The faces of the stop are eccentric with relation to its shank 14^x and by turning the stop any one of its faces may be put into position to be met by the ear e^{14} , consequently varying the position to which the holding plate e^{10} is moved in presenting a top-lift, whereby 50 the proper location of the top-lift with relation to the heel may be insured. The rod f^4 connected with the heel and top-lift holding plate e^{10} is operated as provided for in said patent to move automatically the plate e^{10} into the position, Fig. 8, when a top-lift is to be attached. The plate e^{10} has connected with it, by means of suitable dowel pins and a screw 22, two guideway plates e^{12} and e^{13} . 55 Each of the guideway plates e^{12} and e^{13} (one being shown in section in Fig. 10) has in it two parallel grooves; a back gage e^{20} is provided to position the back of the top-lift, and another e^{21} acts to position the back of the heel. There are two breast gages f^{12} and f^{10} , 60

the former to meet the breast of the top-lift and the latter to meet the breast of the heel. All four gages have similar shanks. The shanks of the two top-lift gages are received in the grooves in the guideway plate e^{13} and those of the two heel gages are received similarly in the guideway plate e^{12} . Each of the breast gages has connected with it a spring 16, the opposite end of which may be hooked into any one of a series of holes 100 in the plate e^{10} according to the size of the heel or top-lift that the spring may always act with uniform pressure against the breast of either the heel or top-lift whatever their size, but the backward movement of said breast gage is or may be limited by a stop shown as a cotter pin 18, adjustable in holes 19 made in the plate e^{10} .

The plate e^{10} has, as represented, a guide block e^{10} , herein represented as of V-shape, 85 see Fig. 8, the converging outer edges of the block being represented as undercut, said side edges receiving respectively the free ends of the heel breast gage f^{10} and the top-lift breast gage f^{12} . The back gages e^{21} and e^{20} have to be adjusted to adapt them to top-lifts and heels of different sizes. The shank of each of said back gages is provided with an extension 17, which receives through it one of two like adjusting screws e^{18} , e^{19} , said screws 90 having their heads provided with annular grooves and sustained in a bridge e^{17} in such manner that said screws may be rotated in said bridge without, however, being at all moved longitudinally, the threads of the 95 screws in engagement with the projection 17 of the back gages putting said back gages into any desired position according to the size of the top-lift or heel. The heel and top-lift holding plate e^{10} , located underneath the breast gage f^{12} and the back gage e^{20} , that hold between them the top-lift, has an extension e^{10x} , see Fig. 8, that acts as a spanner 100 and occupies a position to cover the nail-block a^9 when a top-lift is being spanked on, but said plate is cut away on the line w to leave a space so that the end of a heel applied between the breast gage f^{10} and the back gage e^{21} may contact with the upper 115 side of the nail-block when the plate e^{10} is moved into the position, Fig. 9, to enable a heel to be attached.

In operation let it be assumed that the workman has turned the nail-transferrer from its position, Fig. 8, into its position, 120 Fig. 9, and that the nail-sustainer has been released to supply the nail-block with nails, and that when the transfrerer was coming into the position, Fig. 9, the actuator d^4 turned the heel and top-lift holding plate e^{10} 125 on its pivot pin 12, putting the heel holding space of the plate e^{10} over the nail-block so that the nails leaving the receiver entered the holes in the nail-block. The nail-block, having been supplied with nails, the workman 130

returns the nail-transferrer into its normal position, Fig. 8, leaving the plate e^{10} locked in the position, Fig. 9, by the spring-controlled locking device d^{22} , see Fig. 2. In this position the operator places in the back gage e^{21} the back end of a heel and permits the breast gage f^{10} to contact with the breast of the heel, and puts the rear end of a top-lift into the back gage e^{20} , letting the breast gage f^{12} meet the breast of the top-lift. This done, the operator through usual means starts the heel-nailing machine, and the die-bed spindle, with the nail-block head a^9 and nail-block a^{10} , is lifted, as described, causing the heel resting upon the nail-block to meet and be pressed firmly at its upper end against the end of the sole of the boot or shoe to which the heel is to be attached, said boot or shoe being held on any usual jack. After the heel has been compressed somewhat in the further movement of the machine in usual manner, the drivers d , common to said patent, rise in the holes of the nail-block, and acting upon the heads of the nails drive the nails from the nail-block through the heel and attach the latter to the sole, but the nails are not fully driven, the heads being left protruding sufficiently in usual manner to have spanked upon them the top-lift. During this first rise of the head a^9 the tail d^{23} of the spring-controlled catch d^{22} normally held in the position shown in Fig. 2, meets a tripping device or controller n^2 , notched at n^3 , and pivoted at n' on a projection n fixed to the framework, turns said tripping device about its pivot n' into the dotted line position Fig. 3, and the tail of the catch passes above the tripping device after which the spring n^4 again returns the tripping device to its normal position. After the heel has been attached the die-bed spindle descends, and at this time the tail d^{23} of the spring-controlled locking device meets the edge of the tripping device or controller, which turns the locking device d^{22} in a direction to release the stud d^{19} , extended downwardly from the plate e^{10} , letting said plate be moved or swung automatically by the link f^4 into the position shown by Fig. 8 to carry the top-lift into position to be spanked onto the heel just attached. The top-lift having been brought in position to be spanked onto the partially driven nails, the die-bed spindle again rises, this second rise occurring without the machine having stopped since the first rise and descent, and the top-lift is spanked in usual manner upon the heads of the nails, after which the heads carrying the nail-block and drivers descend into their normal or starting position, and the machine is automatically stopped in usual manner all ready to repeat the operation, as described. During the second descent the stud d^{19} of the heel and top-lift holding plate e^{10} is not in position to be held by the spring-controlled locking device or

catch d^{22} , and said catch is moved, as before described, but without producing any result.

Claims.

1. In a machine of the class described, a horizontally movable nail-transferrer and a nail-sustainer, combined with a horizontally movable nail-guide held out of contact with said transferrer and having holes to receive and guide the nails after leaving said nail-sustainer. 70
2. In a machine of the class described, a transferrer, and a nail-guide, combined with a sustainer movable between said transferrer and guide. 75
3. In a machine of the class described, a nail-block, a transferrer to present nails to the nail-block, and a nail-guide fixed in its position with relation to said transferrer and interposed between the nail-holes of the transferrer and the nail holes in said nail-block to guide the nails after leaving the transferrer on their way into the holes of the nail-block. 80
4. In a machine of the class described, a nail-transferrer, a nail-sustainer, means to hold said sustainer in its operative position while the transferrer is taking nails into position to be driven, and a nail-guide having a series of holes occupying a position in line with the nail holes of said transferrer, combined with means to release said sustainer that the nails supported thereby may leave the transferrer and pass through the holes in said nail-guide. 90
5. In a heel-nailing machine, the combination with nail-driving mechanism, of a nail-transferrer provided with means for sustaining the nails, a nail-guide, and means to actuate the sustaining means when the carrier is moved into nail-delivering position to permit the nails to pass from the nail-guide to the nail-driving mechanism. 100
6. In a heel-nailing machine, a nail-transferrer provided with a nail-receiver to receive nails and present them to a nail block, combined with an independent detachable nail-gage sustained by said nail-receiver and having holes normally in line with the nail holes of said receiver. 110
7. In a heel nailing machine, the combination with a nail receiver chambered at one side, of an unyielding nail gage located in said chamber and means for sustaining said gage fixedly at a distance from the bottom of said chamber. 115
8. A nail-receiver having a series of nail holes for a number of differing nailings, and a detachable nail-gage applied to the upper side of said nail-receiver and having nail holes for a definite nailing, and means to unyieldingly sustain said nail-gage at a distance from the upper side of said receiver. 120
9. In a heel-nailing machine, the combination of a transferrer, a nail-gage sustained above the transferrer, a nail-guide depending 130

from said transferrer, and a nail-sustainer movable out of and in the space between said nail-guide and transferrer.

10. A nail-receiver provided with holes for 5 the reception of nails, combined with a nail-guide having holes in alinement with the holes of the receiver, and means to sustain said guide below and separated from the receiver.

11. In a heel-nailing machine, a transferrer, a shaft having a lug to prevent the starting of the machine except when the transferrer is in its nail-receiving position, and a sliding connection between the shaft 15 carrying said lug and said transferrer.

12. A transferrer, and a nail-guide occupying a position at one side of said transferrer, a nail-sustainer between said transferrer and said nail-guide, a locking device 20 for said sustainer, means to automatically unlock said sustainer, and move it that the nails may enter and pass through the holes of the nail-guide.

13. In a machine of the class described, a 25 horizontally-movable nail transferrer, and a nail-sustainer located at one side of said transferrer, combined with an independent nail guide having holes to receive and guide the nails after leaving the nail holes of said 30 transferrer.

14. In a heel-nailing machine, a plate having a guideway, a breast-gage having its shank entered loosely in said guideway, a back-gage, a spring acting normally to move 35 the breast-gage toward the back-gage, and a stop changeable as to its position on said plate to limit the extent of movement of the breast-gage toward the back-gage.

15. In a heel-nailing machine, a top-lift 40 and heel-carrying plate having a contact piece, and a yieldingly sustained actuator to move said plate and put the heel holding part thereof in operative position.

16. In a heel-nailing machine, a nail-block, 45 a top-lift and heel-carrying plate, a holder upon which said plate is mounted, a yielding catch engaging said plate, and means to adjust said catch to provide for putting the heel in proper position with relation to the nail-block.

17. In a heel-nailing machine, a top lift 55 and heel-carrying plate, a catch to engage and hold said plate while the heel is being attached, a pivotally-sustained yieldingly-actuated tripping device moved by said catch while the latter is being moved in one direction and the heel is being attached to a shoe, said tripping device being arranged to release the catch after said heel has been attached to a shoe.

18. In a heel-nailing machine, a nail-block head, means to raise and lower it, a nail-block, a series of nail drivers, a pivoted heel-carrying plate; a stud connected therewith, 65 and a yielding actuator adapted to meet said

stud and put the heel held in the plate in position to have nails driven into it, said actuator being free to yield if met by a portion descending with the nail-block head.

19. In a heel-nailing machine, a nail-transferrer having an arm extended therefrom, a rod pivotally mounted on said arm, and locking means under the control of said rod to prevent the operation of the machine while the nail-transferrer is in nail-delivering position.

20. In a heel-nailing machine, a movable part to control the starting of the machine, locking means for engaging said movable part and preventing the operation of the machine, a nail-transferrer movable substantially in the arc of a circle between its nail-receiving and nail-delivering positions, an arm extended from said nail-transferrer, and means pivotally connected to one end of said arm and in engagement with a part of said locking means to render the latter inoperative in the nail-receiving position of the nail-transferrer.

21. In a heel-nailing machine, a transferrer having a nail-receiver, an adjustable device carried by said transferrer, and a stop with which said device contacts to arrest the transferrer with the holes of the nail-receiver in position to receive nails, and devices to lock 95 said transferrer in nail-receiving position.

22. In a heel-nailing machine, a plate having a guideway, a breast-gage having its shank held loosely in said guideway, a back-gage, means to move said back-gage to adapt 100 the same to the work to be done, and a spring connected at one end to said breast-gage and at its opposite end adjustably connected to said plate, that the pressure of the breast-gage may be exerted uniformly on the stock 105 held between it and the back-gage whatever its size.

23. In a heel-nailing machine, a plate having an attached guideway plate provided with parallel guideways, a back-gage comprising a notched plate having a shank extended backwardly therefrom at one side of the apex of the notch of said back-gage, said shank entering one of the grooves of said guideway-plate, and a breast-gage comprising 110 a shank having a right-angled arm extended therefrom in one direction, the shank of the breast-gage entering the other groove in said guideway-plate, means to adjust the position of the back-gage, and a spring acting 115 normally to move the breast-gage toward the back-gage.

24. In a machine of the class described, the combination with a horizontally movable nail-transferrer, of a nail-guide movable 125 therewith, and a nail-sustainer independent of said nail-guide arranged to control the passage of nails from the nail-transferrer through the nail-guide.

25. In a machine of the class described, a 130

transferrer, means to sustain the nails therein, a nail-block, and a nail-guide secured to said transferrer and located between said transferrer and nail-block to guide the nails passing from the transferrer into the nail-block.

26. In a machine of the class described, a nail-transferrer arranged for movement from receiving position into delivering position and provided with a receiver having nail passages, combined with a nail sustainer for supporting nails in the nail receiver, and a nail gage mounted upon the receiver and having perforations arranged to register with passages in the receiver, said receiver and nail gage being constructed and arranged to be maintained in different relative positions to accommodate nails of different lengths.

27. In a heel-nailing machine, a nail-transferrer provided with a detachable nail receiver to receive nails and deliver the same into the holes of a nail block, combined with an independent detachable nail gage sustained by said nail receiver, and having holes normally in line with the nail holes in said receiver.

28. In a heel-nailing machine, a top lift and heel-carrying plate, holding means to retain said plate in heel-attaching position

said means being arranged for adjustment to 30 permit said position to be varied, and a tripping device adapted to release said holding means after a heel has been attached to a shoe.

29. In a heel-nailing machine, a movable 35 transferrer to deliver nails to a nail block, a nail guide carried in fixed position upon said transferrer and having holes in line with the nail holes of said transferrer to guide nails on their way into the nail holes of said nail block.

30. In a heel-nailing machine, a movable 40 transferrer to deliver nails to a nail block, a nail guide carried by said transferrer and having holes in line with the nail holes of said transferrer to guide nails on their way into the nail holes of said nail block, and a nail 45 sustainer to sustain the ends of the nails occupying a position in said transferrer and which are subsequently to be discharged from the transferrer through the holes in the nail guide.

In testimony whereof, I have signed my name to this specification, in the presence of two subscribing witnesses.

BENJAMIN F. MAYO.

Corrections in Letters Patent No. 884,513.

It is hereby certified that in Letters Patent No. 884,513, granted April 14, 1908, upon the application of Benjamin F. Mayo, of Salem, Massachusetts, for an improvement in "Heel-Nailing Machines," errors appear in the printed specification requiring correction, as follows: In line 12, page 3, the word spring should read sprung, and in line 85, page 4, the reference character e^{10} should read e^{16} ; and that the said Letters Patent should be read with these corrections therein that the same may conform to the record of the case in the Patent Office.

Signed and sealed this 26th day of May, A. D., 1908.

transferrer, means to sustain the nails therein, a nail-block, and a nail-guide secured to said transferrer and located between said transferrer and nail-block to guide the nails passing from the transferrer into the nail-block.

26. In a machine of the class described, a nail-transferrer arranged for movement from receiving position into delivering position and provided with a receiver having nail passages, combined with a nail sustainer for supporting nails in the nail receiver, and a nail gage mounted upon the receiver and having perforations arranged to register with passages in the receiver, said receiver and nail gage being constructed and arranged to be maintained in different relative positions to accommodate nails of different lengths.

27. In a heel-nailing machine, a nail-transferrer provided with a detachable nail receiver to receive nails and deliver the same into the holes of a nail block, combined with an independent detachable nail gage sustained by said nail receiver, and having holes normally in line with the nail holes in said receiver.

28. In a heel-nailing machine, a top lift and heel-carrying plate, holding means to retain said plate in heel-attaching position

said means being arranged for adjustment to 30 permit said position to be varied, and a tripping device adapted to release said holding means after a heel has been attached to a shoe.

29. In a heel-nailing machine, a movable 35 transferrer to deliver nails to a nail block, a nail guide carried in fixed position upon said transferrer and having holes in line with the nail holes of said transferrer to guide nails on their way into the nail holes of said nail block.

30. In a heel-nailing machine, a movable 40 transferrer to deliver nails to a nail block, a nail guide carried by said transferrer and having holes in line with the nail holes of said transferrer to guide nails on their way into the nail holes of said nail block, and a nail 45 sustainer to sustain the ends of the nails occupying a position in said transferrer and which are subsequently to be discharged from the transferrer through the holes in the nail guide.

In testimony whereof, I have signed my name to this specification, in the presence of two subscribing witnesses.
